UNITED STATES PATENT OFFICE.

GEORGE BRYANTON, OF HARRIMAN, TENNESSEE.

NECK-YOKE CONNECTION.

SPECIFICATION forming part of Letters Patent No. 611,444, dated September 27, 1898.

Application filed May 20, 1898. Serial No. 681,197. (No model.)

To all whom it may concern:

Be it known that I, GEORGE BRYANTON, a citizen of the United States, residing at Harriman, in the county of Roane and State of Tennessee, have invented new and useful Improvements in Neck-Yoke Connections, of which the following is a specification.

My invention relates to improvements in neck-yoke connections, and pertains to a connection having a peculiar form of ball-and-joint construction and a turning connection between the ball and joint and the tip or end of the pole, all of which will be fully described hereinafter and particularly referred to in the claims.

The object of my invention is to provide an improved ball-and-socket connection between the tip or end of the pole and the neck-yoke, and also to provide a swivel-socket between the pole and the ball connection, whereby a universal connection between the pole and the neck-yoke is provided.

In the accompanying drawings, Figure 1 is a perspective view of the end of the pole and the neck-yoke, looking from the inner side thereof. Fig. 2 is a vertical section taken longitudinally through the pole and transverse the neck-yoke. Fig. 3 is a detached perspective view of the ball connections. Fig. 4 is a detached view of the ball clamp or socket. Fig. 5 is a detached view of the bearing which is situated between the ball and the neck-yoke.

Reference being now had to the drawings, A indicates a neck-yoke of the ordinary construction, and A' the pole. A socket a is provided with laterally-projecting ears b, through which and through the neck-yoke pass the clamping-bolts c, carrying on their ends the clamping-nuts d. The socket a has at its inner side a spherical recess e, corresponding in shape to the ball f upon the end of the socket B. The end of the socket B between the ball f and its main portion is flat at each side, as shown at g, and the socket a is provided with a slot h, in which the flat portion g moves.

The opening i is sufficiently large for the ball f to pass through, and in this way the ball is placed within the socket by a lateral movement, as will be readily understood. A washer j is provided which fits over this

opening i, and through the washer one of the clamping-bolts pass. From this description it will be seen that the clamping-bolt opening 55 forms an opening through which the ball f is inserted, though this may be varied and an independent bolt-clamp opening provided.

The socket a is provided with a rectangular recess k at a point inside the spherical 60 recess e, and situated within this rectangular recess is a correspondingly-shaped block D, having one side rounding to fit against the neck-yoke A, and its opposite side provided with a spherical recess m, in which the outer 65 face of the ball f fits. The spherical recess m and the spherical recess e combine together to form a recess in outline a sphere and corresponding in shape to the ball f, as will be readily understood.

Secured upon the end of the pole A' is a tongue G, its inner end having a socket F extending over the pole, as will be readily understood. The outer end of the socket B is adapted to receive the tongue G loosely, so 75 that the ball-socket permits a lateral movement and the socket B and tongue G a transverse movement.

From the above description it will be seen that I have produced a cheap, effective, and 80 durable connection between the neck-yoke and the tongue.

Having thus described my invention, what I claim, and desire to secure by Letters Patent, is—

1. A neck-yoke connection comprising a socket, the said socket provided with a recess at its inner side and with a slot passing therethrough and communicating with the recess and with an opening at one side of the slot larger in diameter than the width of the slot, combined with an arm carrying a ball having a reduced portion at a point inside thereof, whereby the ball is adapted to be inserted through said opening and carried through the slot to its recess, substantially as described.

2. A neck-yoke connection comprising a socket, said socket provided at its inner side with a spherical recess and with a horizontal slot extending across the outer end of the socket, combined with an arm having at its outer end a head or ball provided with a reduced portion at a point inside of the head

or ball, the said socket also provided with an opening larger than the said slot and at one side of the recess, the opening being of a size adapted to permit the head to pass therethrough, the parts operating substantially as and for the purpose described.

3. A neck-yoke connection comprising a socket provided with a recess at its inner side and with a bolt-opening and with a slot extending across the socket and passing therethrough and communicating with the said recess, the bolt-opening communicating with said slot and being larger in diameter than the width of the slot, combined with a tongue having a head or ball of a size adapted to pass through the said bolt-opening and to be seated in the said recess, and a washer fitting over the bolt-opening through which the clamping bolt passes, the parts adapted to operate as described.

4. A neck-yoke connection comprising a socket provided at its inner side with a spherical recess, combined with an arm carrying a ball or head adapted to fit in the recess, the arm having a reduced portion at a point in-

side the head or ball, the socket provided with a slot therethrough communicating with the said recess, and also provided at one side of the slot with an opening larger in diameter than the width of the slot, the socket having at a point inside of said recess a bearing-block recess, a bearing-block fitting within the recess, the bearing-block having at its outer side a spherical opening registering with the spherical opening in the socket, the parts adapted to coöperate as described.

5. A neck-yoke connection comprising a socket, an arm having a ball seated within the socket, the arm having a socket, the pole, the end of the pole provided with a tongue fitting loosely in the said arm-socket, substantially as and for the purpose described.

In testimony whereof I have hereunto set my hand in the presence of two subscribing witnesses.

GEORGE BRYANTON.
